UNITED STATES PATENT OFFICE.

MARTHA F. McCABE, OF BROOKLYN, NEW YORK.

COLLAPSIBLE IRONING BOARD.

Application filed June 30, 1925. Serial No. 40,659.

To all whom it may concern:

Be it known that I, MARTHA F. McCABE, a citizen of the United States, and a resident of the city of New York, borough of Brooklyn, in the county of Kings and State of New York, United States of America, have invented a new and Improved Collapsible Ironing Board, of which the following is a full, clear, and exact description.

10 This invention relates to a collapsible ironing board.

An object is to provide a simple, efficient ironing board of collapsible type which when expanded will be sufficiently large for ordinary use to which it may be put by travellers, will be especially strong and compact, and yet when folded can be usually stowed in a trunk or a suit case.

A further object comprises the provision 20 of a board so constructed that it is extremely simple to open and close, is comprised of a minimum number of simple parts, and does not require any additional parts such as hooks, latch bars, etc., in order to hold it firmly in its operative position; these parts 25 not being required by reason of a strong positive interlocking action between the various parts of the board.

The invention is illustrated in the drawings, in which—

Figure 1 is a perspective view of the ironing board as unfolded ready for use.

Fig. 2 is a longitudinal section taken on the line 2—2 of Fig. 1.

35 Fig. 3 is a cross section on the line 3—3 of Fig. 2.

Fig. 4 is a section through the board when folded ready to be stowed away.

The form of the invention shown in the 40 drawings is a preferred form, although it is understood that modifications in the construction and arrangement of the parts and in the character of the materials used may be adopted without departing from the 45 spirit of the invention as set forth in the appended claims.

In its general aspect the invention comprises a board having a main body portion with foldable end portions which when they 50 are in their operative position form an extension of the main body portion so as to provide an ample length of ironing surface. These end extensions are adapted to be folded back against the top surface of the 55 main body portion when not in use. On the under face of the extension they are pro-

vided with suitable grooves. These grooves are adapted to receive projecting tongues disposed on the upper edge of leg portions which are hinged to the under surface of the main body portion near the ends thereof. These leg portions are also provided with shoulders on which the end of the under surface of the main body portion bear when the legs are moved to their operative position.

In this relation, therefore, the leg portions provide a firm bearing surface for the ends of the body portion and are provided with means which positively and firmly interlock with the foldable end portions or extensions when the parts are operatively assembled. This interlocking action of the extensions, the legs and the main body portion, provide a strong compact unit eliminating the necessity for extra devices such as hooks, latch bars, etc., which otherwise would have to be used.

In the preferred form of the invention shown in the drawing the ironing board 60 comprises a main body portion 10 having hinged to the end thereof extension portions 11 and 12. The hinges 13 for these extension portions are preferably countersunk into the surfaces to which they are fastened as shown in Fig. 1. These extensions are adapted to be disposed in the position shown in Figs. 1 and 2 when in use, and to be folded to the position shown in Fig. 4 when not in use. It will be noted that on the inner under surface of each of the extensions there is provided a groove 14. The ironing board is also provided with two leg portions 15 and 16. It will be noted that the upper edge of each leg portion is provided with a projecting tongue 17, the dimensions of which correspond to the dimensions of the groove 14. It will also be noted that the upper surface of each leg is provided with a shoulder 18 which when the parts are operatively assembled form the bearing surface for the end of the body portion. The legs when not in use are adapted to be folded back against the under surface of the body portion, as shown in Fig. 4.

This folded condition presents a simple, compact device which occupies a minimum amount of space so that it can be readily stowed away in a trunk or suit case, and yet when expanded to the position shown in Figs. 1 and 2 provides a board of very ample dimensions, which can be placed on top

of a dresser, on top of a table, or any convenient place for the use of the traveller. The interlocking action between the groove 14, the tongue 17, the shoulder 18, and the 5 body portion 10, makes the device extremely strong and durable so that the construction remains simple and yet compact.

I claim:

1. A collapsible ironing board which comprises a body portion, foldable end portions pivotally connected to the ends of the body portion, foldable leg portions pivotally connected to the ends of the body portion, and means on the leg portions and the end portions for causing an interlocking action between these portions to hold the parts in a rigid condition when operatively arranged.
2. A collapsible ironing board which comprises a body portion, foldable end portions 15 pivotally connected thereto and having grooves on the under surface thereof, foldable leg portions

pivotally connected to the ends of the body portion and having tongues thereon adapted when the parts are operatively arranged to project into said grooves to lock the parts 25 firmly together.

3. A collapsible ironing board which comprises a main body portion, foldable end portions pivotally connected thereto and having grooves therein, foldable leg portions 30 pivotally connected to the ends of the main body portion, said leg portions having projecting tongues on their upper surfaces adapted to lie in said grooves when the portions are moved to their operative positions, 35 the inner sides of the tongues abutting the ends of the main body portion and the upper ends of the leg portions forming shoulders adapted to abut the ends of the lower face thereof.

MARTHA F. McCABE.
